CLAIM

I claim the ornamental design for a foam roller, as shown and described.

DESCRIPTION

FIG. 1 is a top perspective view of the foam roller showing my new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings depict therapeutic portions of the foam roller that form no part of the claimed design.
